SLICING MACHINE

Joseph Folk, La Porte, Ind., assignor to U. S.
Slicing Machine Company, La Porte, Ind., a
corporation of Indiana

Application August 30, 1943, Serial No. 500,521

8 Claims. (Cl. 146—102)

This invention relates to slicing machines and particularly to a slicing machine having a rotary slicing knife, and a gauge plate for determining the thickness of slices of substance to be cut, which is adjustable simultaneously both obliquely and perpendicularly in relation to the cutting plane of the slicing knife.

An object of this invention is to provide a slicing machine in which a gauge plate is mounted on a slide member for movement to various positions of adjustment in planes parallel to the cutting plane of the slicing knife, and the slide member is arranged for movement in an angular direction in relation to the cutting plane of the slicing knife.

Another object of the invention is to provide a slicing machine employing a rotary slicing knife and an adjustable gauge plate in which the gauge plate is adjustable to a position in the cutting plane of the knife and planes parallel thereto, and the application of power to the slicing knife and the adjustment of the gauge plate are controlled by a common control member, and the operation of the control of the application of power to the knife is possible only when the gauge plate is positioned in alignment with the cutting plane of the knife.

A further object of the invention is to provide means in a slicing machine having an adjustable gauge plate and a rotary slicing knife, for indicating the thickness of a slice to be cut according to the position of adjustment of the gauge plate and the kind of substance to be sliced.

This invention further resides in the combination, construction and arrangement of parts illustrated in the accompanying drawings, and while there is shown therein preferred embodiments of the invention, it is to be understood that the same are susceptible of modification and change without departing from the spirit of the invention.

The accompanying drawings illustrate a selected embodiment of the invention, and the views therein are as follows:

Fig. 1 is a plan view of a machine embodying the invention;

Fig. 2 is a partial vertical section along the line 2—2 of Fig. 1;

Fig. 3 is a partial vertical section along the line 3—3 of Fig. 1;

Fig. 4 is a partial vertical section along the line 4—4 of Fig. 2; and

Fig. 5 is a detail perspective view of certain parts of the machine shown in Fig. 2.

The particular embodiment of the invention

illustrated in the drawings and generally designated by the numeral 6 comprises a base 7, a motor 8 mounted on the base and operatively connected with a shaft 9, rotatably mounted in a support 10 secured on the base 7. A gauge plate 11 is slidably mounted on the base 7 in adjustable spaced relation with a rotary slicing knife 12 which is fixedly mounted on the shaft 9. The gauge plate 11 is fixedly mounted on one end of a carriage or slide member 13. The slide member 13 is in the form of a parallelogram and of dovetail cross-sectional configuration, and is arranged between opposed, parallel guides 14 and 15 for sliding obliquely on the top 16 of the base 7. To this end the guides 14 and 15 are secured to the top 16 by means of screws 17 and disposed angularly in relation to the top so as to conform with the adjacent sides of the member 13. The member 13 and the gauge plate 11 are movable in relation to the base 7 and the knife 12 by means of a manually operable knob 18 which is fixedly mounted upon one end of a shaft 19. The opposite end of the shaft 19 is adapted to be received in a bore at one end of a generally tubular member 20 in releasable interlocking engagement therewith, a pin 21 being provided on the shaft 19 and adapted to be received in a slot 22 in the member 20 for this purpose. The opposite end of the member 20 is provided with a journal portion 20—a. The journal 20—a and the portion of the shaft 19 adjacent the knob 18 are mounted in bearings 23 and 24, respectively, provided interiorly of the base 7; the bearing 23 being mounted on the underside of the top 16 and the bearing 24 being mounted in the bore of a boss 24—b provided in a side wall of the base and secured therein by means of a set screw 24—a.

The member 20 has an externally toothed portion 20—b the teeth 20—c of which are elongated for a purpose hereinafter to be mentioned, and arranged to mesh with the teeth 25—a of a rack 25 which is secured by means of set screws 26 to the underside of the slide member 13. The top 16 is slotted as indicated at 16—a in Fig. 2 to provide for travel of the rack 25. The rack 25 is arranged perpendicularly in relation to the gauge plate 11. The arrangement is such that upon the shaft 19 being interlocked with the member 20 and the knob 18 being rotated, the member 13 and the gauge plate 11 will be moved in relation to the base 7 and the knife 12 according to the direction of rotation of the knob 18. As the member 13 is disposed obliquely with respect to the top 16 and the gauge plate 11, and

the rack 25 is arranged perpendicularly in relation to the gauge plate 11, the rack 25 will travel longitudinally in relation to the axis of the shaft 19 upon rotation of the shaft, making necessary the provision of elongated teeth on the member 20.

It will be readily understood that upon adjustment of the position of the gauge plate 11 by turning the knob 18, the shaft 19 being in locking engagement with the member 20, the gauge plate will be displaced in relation to the cutting plane of the knife 12 in two directions, that is, perpendicularly to the cutting plane of the knife and obliquely thereto, as illustrated in dotted lines in Fig. 1.

It is desirable in a slicing machine of the kind described to have a convenient indication of the position of the gauge plate in relation to the cutting plane of the knife and the corresponding thickness of substance to be cut, especially with reference to particular substance. In order to provide such an indication the present invention includes an indicating device which is mounted upon the upper front portion of the top of the base of the machine. This indicating device is operatively connected with the means for adjusting the position of the gauge plate by means which includes rack teeth 27 which are provided on the front edge of the member 13 for meshing with a gear segment 28 which is rotatably mounted on a stub shaft 29 and carries a pointer 30. The stub shaft 29 may be in the form of a screw arranged in a conveniently disposed threaded opening in the top 16. A cutaway portion 14—a is provided in the guide 14 for receiving the gear segment 28. The pointer 30 is preferably arranged in association with a graduated translucent scale or dial plate 31. The plate 31 may be secured, as by means of screws 32, upon a cover 33, which preferably extends over the entire top 16. The dial plate 31 may be provided with graduations to show the thickness of the slice to be cut and suggested thicknesses of slices for various substances. An electric light (not shown) may be provided to illuminate the indicating device 45 and reflect the thickness of slice to be cut by projecting the shadow of the pointer upon the translucent dial plate.

In addition to regulating the thickness of slices the knob 18 may be utilized to control the application of power to the knife 12. This may be accomplished by means of a sleeve 34 secured on the shaft 19 intermediately of the member 20 and the bearing 24, as by means of a set screw 34—b. The sleeve 34 is provided with an annular groove 34—a adapted to receive one end of a crank 35. The crank 35 is pivotally mounted at 35—a upon a bracket 36 supported on the base 7 and has its opposite end operatively connected with an electric switch 37, which is operatively connected with the motor 8. The arrangement of these parts is such that upon movement of the shaft 19 a predetermined distance longitudinally in relation to its axis, the crank 35 will operate to throw the switch 37 from "off" position to "on" position and vice-versa according to the direction of movement of the shaft 19.

In order that the cutting edge of the slicing knife be guarded to avoid accidental cutting of the hands of the operator when the machine is being loaded, unloaded or cleaned, and the knife is not being operated, the switch control mechanism is arranged so that the switch may be thrown to "off" position only when the gauge plate is at zero position, that is, in substantial

alignment with the knife. For this purpose the shaft 19 is provided with a second pin 38 which is arranged in spaced relation with the pin 21 and so as to abut the inner end of the bearing 24

5 when the pin 21 is within the slot 22 (see Fig. 2) and to be received in a slot 39 extending longitudinally of the bearing 24 from its inner end upon outward movement of the shaft. The pin 38 and slot 39 are so disposed that the slot 39 10 will be in position to receive the pin 38 only when the gauge plate is in zero position as above stated.

A coil spring 40 is arranged within the hollow portion of the member 20 intermediate the inner end of the shaft 19 and the journaled end 15 of the member 20 so as to operate to move the shaft 19 outwardly when the pin 38 is in position to be received in the slot 39. The length of the slots 22 and 39, the position of the sleeve 34 on the shaft 19, and the throw of the switch 37 are 20 so correlated that when the shaft is moved outwardly by operation of the spring 40 the pin 21 will be withdrawn from the slot 22, the pin 38 will be received in the slot 39, and the switch 37 will be thrown from "on" to "off" position. The shaft 19 and the switch 37 will thereafter remain locked in their respective positions until upon inward movement of the shaft 19, as by pressing the knob 18, the pin 38 is withdrawn from the slot 39 and the switch 37 thrown to "on" position, 25 when the knob 18 may be rotated to adjust the position of the gauge plate and lock the switch in "on" position.

Changes may be made in the form, construction and arrangement of the parts without departing from the spirit of the invention, and the right is hereby reserved to make all such changes as fairly fall within the scope of the following claims.

The invention is hereby claimed as follows:

40 1. A slicing machine comprising a base, a rotary slicing knife fixedly mounted on said base, motive means operatively connected with said knife, means for controlling the operation of said motive means, a gauge plate movably mounted on said base in adjustable spaced relation with said knife, means for controlling the adjustment of the position of said gauge plate, and means operatively connected with the means for controlling the adjustment of the position of the gauge plate and the means for controlling the operation of the motive means whereby to prevent operation of the means for controlling the operation of the motive means except when the gauge plate is in a predetermined position of adjustment.

45 2. A slicing machine comprising a base, a rotary slicing knife fixedly mounted on said base, motive means operatively connected with said knife, means for controlling the operation of said motive means, a gauge plate, a member movably mounted on said base for supporting said gauge plate in adjustable spaced relation with said knife, manually operable means mounted on said base and operatively connected with said member for moving said member in relation to said base, and means operatively connected with the means for controlling the operation of the motive means and said manually operable means

50 60 65 70 75 for preventing operation of the means for controlling operation of the motive means except when the gauge plate is in a predetermined position of adjustment.

3. A slicing machine comprising a base, a rotary slicing knife fixedly mounted on said base, motive means operatively connected with said

knife, means for controlling the operation of said motive means, a gauge plate, a member movably mounted on said base for supporting said gauge plate in adjustable spaced relation with said knife, manually operable means mounted on said base and operatively connected with said member for moving said member in relation to said base, said manually operable means comprising a rack fixedly mounted on said member and a gear rotatably mounted on said base in cooperative relation with said rack, said rack and gear being so arranged and conformed that upon operation of said gear said gauge plate will be translated in relation to the cutting plane of said knife, and means operatively connected with the means for controlling the operation of the motive means and said manually operable means for preventing operation of the means for controlling operation of the motive means except when the gauge plate is in a predetermined position of adjustment.

4. A slicing machine comprising a base, a rotary slicing knife fixedly mounted on said base, motive means operatively connected with said knife, means for controlling the operation of said knife, means for controlling the operation of said motive means, a gauge plate movably mounted on said base in adjustable spaced relation with said knife, said gauge plate being arranged for adjustment of its position in relation to the cutting plane of said knife, means for controlling the adjustment of the position of said gauge plate, means operatively connected with the means for controlling the adjustment of the position of the gauge plate and the means for controlling the operation of the motive means whereby to prevent operation of the means for controlling the operation of the motive means except when the gauge plate is in a predetermined position of adjustment, and means operatively connected with said gauge plate for indicating its position in relation to said knife.

5. A slicing machine comprising a base, a rotary slicing knife fixedly mounted on said base, motive means operatively connected with said knife, means for controlling the operation of said knife, means for controlling the operation of said motive means, a gauge plate movably mounted on said base in adjustable spaced relation with said knife, said gauge plate being arranged for adjustment of its position in relation to the cutting plane of said knife, and means for controlling the adjustment of the position of said gauge plate, said last mentioned means being operatively interconnected with said means for controlling the operation of the motive means whereby operation of the means for controlling the operation of the motive means will be prevented except when the gauge plate is in a predetermined position in relation to the cutting plane of the knife.

6. A slicing machine comprising a base, a rotary slicing knife fixedly mounted on said base, motive means operatively connected with said knife, means for controlling the operation of said motive means, a gauge plate movably mounted on

said base in adjustable spaced relation with said knife, said gauge plate being arranged for adjustment of its position in relation to the cutting plane of said knife, means for controlling the adjustment of the position of said gauge plate, said last mentioned means being operatively interconnected with said means for controlling the operation of the motive means whereby operation of the means for controlling the operation of the motive means will be prevented except when the gauge plate is in a predetermined position in relation to the cutting plane of the knife, and means operatively connected with the means for controlling the adjustment of the position of the gauge plate for indicating the thickness of a slice of substance to be cut for a selected position of adjustment of the gauge plate.

7. A slicing machine comprising a base, a rotary slicing knife fixedly mounted on said base, motive means operatively connected with said knife, means for controlling the operation of said motive means, a gauge plate movably mounted on said base in adjustable spaced relation with said knife, said gauge plate being arranged for adjustment of its position in relation to the cutting plane of said knife, means for controlling the adjustment of the position of said gauge plate, means operatively connected with the means for controlling the adjustment of the position of the gauge plate and the means for controlling the operation of the motive means whereby to prevent operation of the means for controlling the operation of the motive means except when the gauge plate is in a predetermined position of adjustment, and means operatively connected with the means for controlling the adjustment of the position of the gauge plate for indicating a selected thickness of slice of substance to be cut whereby the position of the gauge plate in relation to the cutting plane of the knife may be adjusted to provide for the cutting of a slice of substance of a selected thickness.

8. A slicing machine comprising a base, a rotary slicing knife fixedly mounted on said base, motive means operatively connected with said knife, means for controlling the operation of said motive means, a gauge plate movably mounted on said base in adjustable spaced relation with said knife, said gauge plate being arranged for adjustment of its position both obliquely and perpendicularly in relation to the cutting plane of said knife simultaneously, means for controlling the adjustment of the position of said gauge plate, and means operatively connected with the means for controlling the adjustment of the position of the gauge plate and the means for controlling the operation of the motive means whereby to prevent operation of the means for controlling the operation of the motive means except when the gauge plate is in a predetermined position of adjustment.

JOSEPH FOLK.
